UNITED STATES PATENT OFFICE.

JOSEF LAUBER, OF VIENNA, AUSTRIA-HUNGARY.

MAGAZINE-RIFLE.

No. 855,896.

Specification of Letters Patent.

Patented June 4, 1907.

Application filed April 19, 1906. Serial No. 312,545.

To all whom it may concern:

Be it known that I, JOSEF LAUBER, a subject of the Emperor of Austria, and residing at No. 15 Laxenburgerstrasse, Vienna, Austria, have invented new and useful Improvements in Magazine-Rifles, of which the following is a full, clear, and exact description.

The present invention relates to that class of rifles in which the cartridge is introduced laterally into the barrel in front of the breech block, then pushed forward by the latter into the breech, locked and fired by releasing the firing pin and the object of the invention is to effect the forward movement of the breech block and locking of the same by means of the pull of the trigger. Thus the first part of the pull of the trigger will force the breech block forward, thrust the cartridge home in the breech and lock the block in position, after which by the further movement of the trigger an auxiliary trigger will be operated and thus release the firing pin to discharge the cartridge.

In order to render the present specification easily intelligible reference is had to the accompanying drawing in which similar numerals of reference denote similar parts throughout the several views:—

Figure 1 is a part longitudinal section through the breech block and trigger mechanism of a rifle carried out according to the present invention, showing the position of the parts at the moment of firing. Fig. 2 is a similar part section showing the position of the parts after the trigger has been released. Fig. 3 is a similar section showing a modified form of the invention with the parts in a similar position to that occupied by them in Fig. 1. Fig. 4 is a similar section of the modification of Fig. 3 with the parts corresponding in position to those of Fig. 2. Fig. 5 is a plan view of a detail and Fig. 6 a cross section through the magazine.

Referring first to Figs. 1, 2, 5 and 6:—The breech block and trigger mechanism housing consists of the upper and lower walls 2 and 3, the rear wall 4 and a horizontal partition wall 6 dividing the said housing into the upper breech block casing to the front end of which the barrel 1 is attached having the cartridge seating or breech 5, while the trigger mechanism is mounted in the lower chamber.

It may here be stated that the magazine (Fig. 6) is of known construction consisting of the two walls 53, 54 having the feed springs 52 for forcing the cartridge laterally

into the breech as will be readily understood. Both the cartridge feed as also the extracting and ejecting mechanism may be of any suitable known construction. The cartridge 33 is fed laterally to the breech in front of the breech block and is forced home by the latter, but the movement of the breech block to perform this operation is derived from the trigger mechanism. The trigger 12 is mounted on a stationary pivot 10 and has rigidly connected thereto a tooth segment 11 which engages with a segment 9 rigidly connected to one arm of a lazy tongs 7. The rear end of the tongs is fast on the pivot 8 to which the segment 9 is attached and when the trigger is pulled back the lazy tongs will be stretched out forwardly. The front end of the lazy tongs is linked to an arm 14 made in one piece with, or rigidly attached to the breech block 15 and extending downwardly through and guided in a slot of the wall 6. The breech block 15 carries within it the firing pin 20 the shaft 17 of which extends out through a boring in the rear closing screw 80 head 16 and carries outside the block the downwardly extending lug 18.

Mounted on a stationary pivot 22 at the rear of the trigger 12, is the firing trigger 23, having an upwardly extending arm 25 adapted to coöperate with the firing pin detent lever 26, 27 mounted on a stationary pivot and having its nose 27 extending into the path of movement of the lug 18 of the firing pin. This detent lever is normally held against a stop 35 by means of a spring 28 and when the firing lever is pressed backward by means of the button 24 on the lower rear side of the trigger 12, it forces the detent lever to the position shown in Fig. 1, from under the lug 18 and releases the firing pin to discharge the cartridge under the action of the main spring 19. As soon as the trigger 12 has been released the spring 29 returns the breech block and all the parts to their position of rest as indicated at Fig. 2. The backward movement of the main trigger 12 is limited by a spring stop 21 having two cam shaped projections between which the part 12' of the trigger engages when it has reached its backward limit of pull. On releasing the trigger the spring 29 will pull the trigger free of the spring stop owing to the strength of the former and the elasticity of the latter.

The breech block is locked in its forward position while the cartridge is being fired by

the following mechanism: Pivoted to a stationary pivot 44 is a bell crank lever, 45 46, the longer arm 45 of which operates two vertically movable locking bolts 47 and 48 which are normally held away from the breech block 15 by means of their respective springs 49 and 50. These bolts pass upwardly through the wall 6 and the rear one 47 which has an inclined rear surface engages behind a downwardly projecting catch 42 on the breech block, which catch moves in a horizontal slot 51 of the upper part of the wall 6, while the bolt 48 engages in a recess 43 of the breech block, both engagements taking place when the block is in its forward position. This is effected in the following manner:—The shorter arm 46 of the bell crank lever lies in the path of movement of the arm 14 of the breech block and as the latter reaches the end of its forward stroke, it strikes the short end 46 of the bell crank lever raising the arm 45 and forcing the two locking bolts 47 and 48 into engagement with their respective parts of the breech block thus securing it against backward movement while the cartridge is being fired. On releasing the trigger the bolts 47 and 48 are withdrawn by their springs 49 and 50 and the breech block is returned to its initial position while the next cartridge is being fed to the breech. The rear end of the breech bolt chamber is closed by a screw 30.

Instead of the lazy tongs of Figs. 1 and 2 the lever arrangement of Figs. 3 and 4 may be employed. This arrangement consists of a lever 40 mounted on a stationary pivot 39 of the housing and having a slot 38 in which a pin 37 engages mounted on the end 40 of an upper prolongation 36 of the trigger 12. The lower end of the lever 40 is linked to a lever 41 which is linked in its turn to the breech block 15. In this case the spring 29 is attached to the upwardly extending arm 36 of the trigger 12. Thus as will be readily understood on reference to Figs. 3 and 4, when the trigger is pulled back the levers 40 and 41 will force the breech block forward, when the same will be locked in its forward position by means of the contact of the lever arm 41 with the short arm 46 of the bell crank lever 45, 46 in a similar manner to that described with reference to Fig. 1.

The operation of the device which will be readily understood from the foregoing description takes place, briefly described in the following manner:—While the cartridge 33 is being fed to the breach the parts are in the position shown in Fig. 2. As soon as the trigger is pulled backward the lazy tongs 7 of Figs. 1 and 2 or the levers 40 and 41 of Figs. 3 and 4

are immediately extended forcing the breech block 15 forward and pushing the cartridge home. As the breech block advances it will carry the firing pin with it until the stop 27 arrests the lug 18, after which the block will advance alone the firing pin being held back against the pressure or tension of the main spring. On continuing the backward pull of the trigger the cartridge will be forced home 70 in the breech and the locking bolts 47, 48 will be forced up into engagement with the locking devices of the breech block, by the arm 14 operating the bell crank lever 45, 46 so that the breech block will be securely 75 locked in its operative position forward. The further pull back of the trigger 12 will cause the button 24 to push the trigger 23 backward, thus upsetting the tumbler or detent 27 against the action of its spring and 80 releasing the firing pin which flies forward under the action of the main spring and fires the cartridge. As soon as the trigger 12 is released the parts are returned to their initial position by the action of the spring 29. 85

The details of construction might be varied in a great many ways without departing from the spirit of the invention.

I claim as my invention:—

1. In a magazine fire-arm having lateral cartridge feed, trigger mechanism and a sliding breech block, the combination of an arm on the breech block extending into the casing containing the trigger mechanism, a lazy tongs connection from said arm to the trigger mechanism and a spring to return the parts to their initial position after the trigger has been released.

2. In a magazine fire-arm having lateral cartridge feed, a trigger mechanism and sliding breech block, the combination of means for forcing the breech block forward when the trigger is pulled back, means for arresting the firing pin before the breech block has attained its forward position, means for locking the breech block in its forward position consisting of vertically movable bolts springs to normally retain them out of engagement, and a bell crank lever operated by the forward movement of the block to force said bolts up to engage the breech block and lock the same, means for releasing the firing pin when the breech block has been locked and means for returning the parts to their initial position as soon as the trigger has been released.

In testimony whereof I affix my signature in the presence of two witnesses.

JOSEF LAUBER.
